UNITED STATES PATENT OFFICE.

CEPHAS B. ROGERS, OF DANBURY, CONNECTICUT.

DESIGN FOR A CEILING FIXTURE FOR ELECTRIC LIGHTS.

Application filed March 25, 1924. Serial No. 9,067. Term of patent 3½ years.

To all whom it may concern:

Be it known that I, CEPHAS B. ROGERS, a citizen of the United States, residing at Danbury, county of Fairfield, and State of Connecticut, have invented a new, original, and ornamental Design for Ceiling Fixtures for Electric Lights, of which the following is a specification, reference being had to the accompanying drawing, forming part thereof.

Fig. 1, is an edge view, and Fig. 2, a view

of the under side of a ceiling fixture for electric lights, showing my new design.

I claim:—

The ornamental design for a ceiling fixture for electric lights, as shown.

CEPHAS B. ROGERS.
